EDWIN W. BEARDSLEY, OF CHESHIRE, CONNECTICUT, ASSIGNOR TO THE AMERICAN BRASS COMPANY, OF WATERBURY, CONNECTICUT, A CORPORATION OF CONNECTICUT.

NON-OXIDIZING ANNEALING-FURNACE AND MECHANISM FOR HANDLING WORK THEREIN.

1,362,555.

Specification of Letters Patent.

Patented Dec. 14, 1920.

Application filed June 17, 1920. Serial No. 389,553.

To all whom it may concern:

Be it known that I, EDWIN W. BEARDSLEY, a citizen of the United States, residing at Cheshire, county of New Haven, State of Connecticut, have invented a certain new and useful Improvement in Non-Oxidizing Annealing-Furnaces and Mechanism for Handling Work Therein, of which the following is a full, clear, and exact description.

10 My invention relates to a new and improved non-oxidizing annealing furnace and mechanism for handling work therein for introducing material to be annealed into the furnace or removing it therefrom after it has been annealed or for both introducing and removing it and has for its object the maintenance of the work in a horizontal position during the time when it is being introduced or removed through liquid or gas sealed ends of the furnace and the avoidance of injury to the work which is caused by some other means previously used for introduction or removal. It further has for its object improved means for introducing 25 the object and causing it to move through the furnace.

The following is a description of an embodiment of my invention, reference being had to the accompanying drawings, in which, 30 Figure 1 shows a longitudinal section of a retort furnace embodying my invention;

Fig. 2 shows a section on the line 2—2, Fig. 1;

Fig. 3 shows a section of the furnace on 35 the line 3—3, Fig. 1, while

Fig. 4 shows a section on the line 4—4, Fig. 1.

Referring more particularly to the drawings, 1 is the heating chamber of a furnace 40 constructed of refractory materials 2, such as are commonly used. 3 is an oil or gas burner for supplying a combustible mixture to the heating chamber from which combustion gases pass out of the heating chamber of the furnace through the flue 4. 5 is a retort or muffle, which may be used, the same being made of metal or of refractory material and extending through the heating chamber of the furnace. 6 and 7 are continuations or extensions of the retort. They have mouthpieces 8 and 9 depending below the top surface of water 10 in tanks 11 and 12 respectively, which water acts as a seal

and prevents air from entering the retort through these openings. A steam supply 55 pipe 13 with a valve 14 provides for the admission of steam for displacing the air in the retort 5, outlets 15, 16 for which are connected to the interior of the retort at one of their ends and sealed at the other ends by 60 the water 10. 17 is a plunger actuated by a hydraulic cylinder 18 or other suitable means for advancing the work into and through the retort from a charging table at one end and on to a receiving table at the 65 other end.

19—19 are movable tables upon which boxes 20 or other objects are carried through the mouthpieces of the retort and the seals therefor when being introduced into the retort or removed therefrom. Each table 19 is supported by a pair of arms 21—21, which are of equal length and securely attached to the shaft 22 so as to lie in the same plane. This shaft 22 extends through the tanks 70 75 11—12 so that as the shaft is oscillated the tables swing within the tanks. This shaft carries a gear 23, secured thereto, which gear is engaged by a rack 24 actuated by a hydraulic cylinder 25 or other suitable means 80 so as to be oscillated thereby. This rack is provided with adjusting screws 26 whereby its movement in either direction can be positively limited so that the upward movements of the tables can be positively stopped at the 85 desired points.

In order to keep the tables 19 in a horizontal position during their movements, I employ links 27 pivotally connected to the tables and to fixed stationary abutments 28 90 so as to be parallel to the arms 21, the lengths of links being equal to the lengths of the arms 21. I preferably connect the arms 21 and the links 27 by links 30, whose lengths are equal to the distance between the 95 axes of the shaft 22 and the abutments 28, said links being parallel to the plane passing through the shaft 22 and the abutments 28.

The links 30 work on studs 31 on the arms 21, and studs 32 on the links 27. The arms 100 21 work on studs 33 on the table. Links 27 work upon studs 34 upon the table.

From the foregoing it will be seen that the center distances from the shaft 22 to the studs 31 and 33 are equal to the center distances from the stud or abutment 28 to the

studs 32 and 34, and that the center distances between the shaft 22 and the stud or abutment 28 is equal to the center distances between the studs 31 and 32 and between the studs 33 and 34. The distances between axial centers determine the lengths of the several arms and links. The centers of the shaft 22 and the studs 33-33 are in the same radial plane and the centers of the studs 28-28 and studs 34-34 are also in a common plane, and a plane passing through the axial center of the shaft 22 and the axial centers of the studs 33-33 is parallel to a plane passing through the axial centers of the studs 28-28 and the axial centers of the studs 34-34.

The links 30-30 under eccentric loading of the tables 19, and particularly when the bearings become worn, insure correct movement from the bottom or dead center position, in which the arms 21 and links 27 are in the same vertical plane.

In operating this furnace with my apparatus the shaft 22 is turned by means of the cylinder 25, rack 24 and gear 23 to bring the tables 19 to the upper position indicated by dotted lines in Fig. 2, where a box 20 of work to be annealed is placed upon the charging table. The shaft 22 is then, by means of the rack 24 and cylinder 25, revolved in a clockwise direction that carries the table through a path which describes a portion of a circle, entering the water in the tank and passing under the shaft 22 to the other side of the vertical plane passing through that shaft and then above the lower edge of the mouth of the retort extension, whence it passes out of the water and into the position indicated in full lines in Fig. 2, in alignment with the bottom of the retort. The plunger 17 is then operated and the box 20 on the charging table is thereby pushed off its table onto the floor of the muffle. In doing this the boxes which had been previously placed in the retort are pushed ahead the length of one box, thus moving one box from the floor of the retort to the receiving table 19 at the opposite end of the retort.

A reversal of the movement of the shaft 22, by means of the rack 24, carries the box just pushed off from the bottom of the retort through the water in the tank 12, raising it finally to the position shown in dotted lines in Fig. 2, where it is removed before the repetition of the cycle above described.

By the means described a box or other object is introduced into the receiving end of the retort by a swinging movement through a liquid seal, the supporting table being maintained horizontal at all times. By a similar means a box is removed from the discharge end of the retort in a similar manner and the introduction of one box into the body of the retort results in the removal

of a similar article from the body of the retort to the receiving table.

As will be obvious, the two introducing and removing mechanisms need not be operated from the same shaft, nor bear the particular relations described to the longitudinal axis of the retort as are herein shown and described, and, further, the use of water in tanks may be omitted or the water may be displaced by any other suitable medium. Further, it is obvious that some of the advantages of my invention may be attained by the use of one of the two similar box handling mechanisms, the other being replaced by some other mechanism, or omitted entirely where a furnace has but a single mouthpiece used for the removal as well as the introduction of the object to be treated. It is further unnecessary that the non-oxidizing atmosphere be maintained by means of a retort, other means for maintaining such non-oxidizing atmosphere being known in furnaces adapted to be provided with depending mouthpieces closed by fluid seals.

In order that there be no interference the arms 21 are located on the same side of either of the links 27 and when two links are used the planes of the arms 21 are between the planes of the links 27. The links 30 are in a plane lying between its link 27 and adjacent arm 21.

As will be evident to those skilled in the art my invention permits of various modifications without departing from the spirit thereof or the scope of the appended claims.

What I claim is:

1. In an apparatus of the character described, the combination of a horizontal table, an oscillating shaft, two equal arms in the same radial plane mounted upon said shaft and pivotally connected to said table, a connecting link of the same length as said arms and pivoted to said table and to a stationary abutment below said shaft so as to lie in a plane parallel to said radial plane, said arms moving in transverse planes lying on the same side of said link, and means for turning said shaft about its axis so as to move said arms and said table beneath said shaft.

2. In an apparatus of the character described, the combination of a horizontal table, an oscillating shaft, two equal arms in the same radial plane mounted upon said shaft and pivotally connected to said table, a connecting link of the same length as said arms and pivoted to said table and to a stationary abutment below said shaft and in the vertical plane passing through said shaft so as to lie in a plane parallel to said radial plane, said arms moving in transverse planes lying on the same side of said link, and means for turning said shaft about its axis so as to move said arms and said table beneath said shaft.

3. In an apparatus of the character described, the combination of a horizontal table, an oscillating shaft, two equal arms in the same radial plane mounted upon said shaft and pivotally connected to said table, connecting links of the same length as said arms and pivoted to said table and to stationary abutments below said shaft so as to lie in a plane parallel to said radial plane, 10 said arms moving in transverse planes lying between the planes of movement of said links, and means for turning said shaft about its axis so as to move said arms and table beneath said shaft.
- 15 4. In an apparatus of the character described, the combination of a horizontal table, an oscillating shaft, two equal arms in the same radial plane mounted upon said shaft and pivotally connected to said table, 20 connecting links of the same length as said arms and pivoted to said table and to stationary abutments below said shaft so as to lie in a plane parallel to said radial plane, said arms moving in transverse planes lying 25 between the planes of movement of said links, means for turning said shaft about its axis so as to move said arms and table beneath said shaft, and linking members pivotally connected to said arms and parallel links so as to be always parallel to the plane passing through the axial centers of 30 said links and arms at their corresponding ends.
- 35 5. In an apparatus of the character described, the combination of a horizontal table, an oscillating shaft, two equal arms in the same radial plane mounted upon said shaft and pivotally connected to said table, a connecting link of the same length as said 40 arms and pivoted to said table and to a stationary abutment below said shaft so as to lie in a plane parallel to said radial plane, said arms moving in transverse planes lying 45 on the same side of said link, means for turning said shaft about its axis so as to move said arms and said table beneath said shaft, and a furnace having a downwardly opening mouthpiece adapted to be sealed by a 50 fluid seal and within which said table enters at the end of one of its upward movements.
- 55 6. In an apparatus of the character described, the combination of a horizontal table, an oscillating shaft, two equal arms in the same radial plane mounted upon said shaft and pivotally connected to said table, a connecting link of the same length as said 60 arms and pivoted to said table and to a stationary abutment below said shaft so as to lie in a plane parallel to said radial plane, said arms moving in transverse planes lying 65 on the same side of said link, means for turning said shaft about its axis so as to move said arms and said table beneath said shaft, a furnace having a downwardly opening mouthpiece adapted to be sealed by a fluid seal and within which said table enters at the end of one of its upward movements, and a tank surrounding said mouthpiece and shaft and within which said table swings, said tank being adapted to contain a fluid seal.
7. In an apparatus of the character described, the combination of a horizontal table, an oscillating shaft, two equal arms in the same radial plane mounted upon said 75 shaft and pivotally connected to said table, a connecting link of the same length as said arms lying in a plane parallel to said radial plane and pivoted to said table and to a stationary abutment below said shaft so as to 80 lie in a plane parallel to said radial plane, said arms moving in transverse planes lying on the same side of said link, means for turning said shaft about its axis so as to move said arms and said table beneath said 85 shaft, a furnace having a downwardly opening mouthpiece adapted to be sealed by a fluid seal and within which said table enters at the end of one of its upward movements, a tank surrounding said mouthpiece and 90 shaft and within which said table swings, said tank being adapted to contain a fluid seal, means for stopping said table when even with the floor of said furnace, and a plunger adapted to be moved over the top 95 of said table when it is even with the bottom of said furnace and transfer an object from said table to the bottom of said furnace.
8. In an apparatus of the character described, the combination of two horizontal 100 tables, an oscillating shaft, two pairs of equal arms secured thereto so as to lie in the same radial plane, said arms being connected to said tables respectively, links pivotally connected to said tables and to fixed 105 abutments respectively, said links being equal in length to said arms and lying in a plane parallel to said radial plane, said abutments being below said shafts, a furnace having two downwardly opening mouthpieces, adapted to be sealed with fluid seals, and within which said tables are adapted to enter respectively so as to be in alinement with the floor of said furnace at the same time, and a plunger adapted to be moved 110 over one of said tables when it is in such alinement so as to simultaneously move an object from said table to the furnace floor and another object from the floor to the other table, and means for oscillating said 115 shaft.

EDWIN W. BEARDSLEY.
